CLAIM

The ornamental design for finger weight, as shown and described.

DESCRIPTION

FIG. 1 is a perspective elevational view of a finger weight according to my design;

FIG. 2 is a front elevational view thereof, the rear end elevational view thereof being a mirror image of FIG. 2;

FIG. 3 is a right elevational view thereof, the left elevational view thereof being a mirror image of FIG. 3;

FIG. 4 is a top plan view thereof; and,

FIG. 5 is a bottom plan view thereof.

The broken line showing of a finger in FIG. 1 is for illustrative purposes only and forms no part of the claimed design.
